(57) **CLAIM**

The ornamental design for a portable light, substantially as shown and described.

DESCRIPTION

FIG. 1 is a perspective view of an ornamental design for a portable light;

FIG. 2 is a side view of a first side of the design for a portable light, of which the opposite side is a mirror image;

FIG. 3 is a side view of a second side of the design for a portable light;

FIG. 4 is a side view of a third side of the design for a portable light;

FIG. 5 is a view of a first end of the design for a portable light; and

FIG. 6 is a view of a second end of the design for a portable light; and,

FIG. 7 is an enlarged view of a portion of the cylindrical part of the portable light as indicated by the dashed circle and number "7" in FIG. 1.

The broken lines represent unclaimed portions of the article and form no part of the claimed design. The dashed cross-hatching on the cylindrical portion of the portable light indicates an unclaimed surface feature on the claimed cylindrical surface of the portable light. The portable light is shown with a symbolic break in its length, with the understanding that the portions of the light not shown in the drawings form no part of the claim design.
